NIGHT LAMP

James H. Rich, Penn-Wynne, Pa.

Application January 28, 1952, Serial No. 18,255

Term of patent 14 years

(Cl. D48—20)

To all whom it may concern:

Be it known that I, James H. Rich, a citizen of the United States, residing in Penn-Wynne, county of Montgomery, and State of Pennsylvania, have invented a new, original, and ornamental Design for Night Lamp, of which the following is a specification, reference being had to the accompanying drawing, forming a part hereof.

Fig. 1 is a top perspective view of a night lamp showing my new design; and

Fig. 2 is a top plan view thereof.

The dominant features of my design are shown in solid lines.

I claim:

The ornamental design for a night lamp, substantially as shown and described.

JAMES A. RICH.
